UNITED STATES PATENT OFFICE.

JOHN B. VAN HOUTEN, OF NEWARK, NEW JERSEY.

DESIGN FOR AN EAR-RING AND PENDANT.

SPECIFICATION forming part of Design No. 14,518, dated December 25, 1883.
Application filed July 23, 1883. Term of patent 7 years.

To all whom it may concern:

Be it known that I, JOHN B. VAN HOUTEN, a citizen of the United States, residing at Newark, in the county of Essex and State of New Jersey, have invented and produced a new and original Design for Ear-Rings and Pendants; and I do hereby declare the following to be a full, clear, and exact description of the same, such as will enable others skilled in the art to which it appertains to make and use the same, reference being had to the accompanying drawings, and to letters of reference marked theron, which form a part of this specification.

15 In said drawings, Figure 1 is a front elevation, and Fig. 2 an end view, of my newly-designed ear-ring or pendant, which fully illustrate the appearance of the same.

20 The leading feature of this design is in the pendant formed substantially as shown and hereinafter described.

In said drawings, A is a supporting plate, from which the pendant embodying the leading feature of the design is suspended. The pendant at B has a bifurcated shape, the extremities of the bifurcation at E being knob-shaped. Between the arms of the bifurcated portion of the pendant the said pendant has an angular box-shaped conformation, of which conformation the knob-shaped protuberances 30 lie at about the center of the side surfaces, D.

What I claim is—

The design for a pendant of an ear-ring, substantially as herein shown and described.

In testimony that I claim the foregoing I have 35 hereunto set my hand this 19th day of June, 1883.

JOHN B. VAN HOUTEN.
